CLAIM

The ornamental design for a handheld scale with modern design, as shown and described.

DESCRIPTION

This application claims the benefit of U.S. design Pat. No. D521,889 filed on Feb. 1, 2005, U.S. design Pat. No. D448, 316 filed on Feb. 9, 2001 and U.S. Pat. No. 6,833,515 filed Oct. 31, 2002.

FIG. 1 is a perspective view of my new handheld scale with modern design

FIG. 2 is a top view of my new handheld scale with modern design

FIG. 3. is a bottom view of my new handheld scale with modern design

FIG. 4 is a left side view of my new handheld scale with modern design

FIG. 5 is a right side, upside-down view of my new handheld scale with modern design

FIG. 6 is a back side view of my new handheld scale with modern design

FIG. 7 is a front side view of my new handheld scale with modern design; and,

FIG. 8 is a closed-cover perspective view of my new handheld scale with modern design.

My handheld scale with modern design is characterized by a case with a cover that functions as a weighing tray with a weighing table in a square shape with a rectangular-shaped LCD display that is adjacent to functional buttons in a circular display.
